UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

1,356,002.

Specification of Letters Patent. Patented Oct. 19, 1920.

Application filed March 1, 1919. Serial No. 279,940.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

The object of the invention is to provide a friction shock absorbing mechanism especially adapted for railway draft riggings and which is of such form that it may be manufactured at comparatively small expense and wherein all the parts are compactly arranged and adapted to be entirely confined between the sills.

In the drawings forming a part of this specification, Figure 1 is a part elevational view, part longitudinal vertical section of a portion of a railway draft rigging showing my improvements in connection therewith. Fig. 2 is a horizontal, sectional view taken substantially on the line 2—2 of Fig. 1. Fig. 3 is a vertical, transverse, sectional view taken substantially on the line 3—3 of Fig. 1. Fig. 4 is a detail perspective of one of the laterally movable friction elements. And Fig. 5 is a detail perspective of one of the end central friction elements.

In said drawing, 10—10 denote channel-shaped or center draft sills of a railway car, to the inner faces of which are secured the usual front and rear stops 11—11, the spacing between said stops being $18\frac{1}{2}$ ", as illustrated in the drawing. A draw bar 12 is employed, to which is riveted a yoke strap 13 of well known form, all of the parts being supported by a suitable saddle plate 14. Front and rear followers 15 and 16 are used in a well known manner, as most clearly shown in Fig. 2.

The improved shock absorbing mechanism, as shown, comprises end wedges A—A, central or intermediate friction elements B—B, laterally movable or side friction elements C—C, spring D and pressure plates E—E.

The wedges A—A are preferably four in number, two at each end, and each of said wedges is of substantially equilateral tri-

angular formation in cross section. Each of said wedges A—A is adapted to slide transversely relatively to the corresponding follower against which it bears, and it is of course, evident that said wedges will move longitudinally or parallel to the line of draft in accordance with the particular follower being actuated.

Each side or lateral friction element C extends longitudinally between two of the friction wedges A—A and, as shown, each element C is provided on its inner face at each end thereof with a vertically extending wedge surface 17 coöperable with the corresponding adjacent outer surface of a wedge A. In addition, each of said elements C is formed with a plurality, preferably three, integral inwardly and laterally extended loops 18—18, the same being vertically separated as clearly shown in Figs. 3 and 4 so that the two of said elements C may be assembled with the loops 18 of the one slidably passing between the loops of the other, as shown most clearly in Fig. 3. When thus assembled, it is evident that a substantially rectangular pocket is formed within which is adapted to be received the two-coil spring D, the spring D being inserted after the two elements C are properly assembled.

Each of the elements B is formed on its outer end with a pair of vertically extended wedge faces 19—19 adapted to coöperate with the opposed wedge faces of the two adjacent wedge blocks A—A, as clearly shown in Fig. 2. The inner face of each element B is flat or plain, as indicated at 20, and may bear slightly against the loops 18 of the two assembled friction elements C—C. In order, however, to eliminate or at least minimize pressure against the loops 18 in a direction parallel to the center line of draft, I employ the two pressure receiving plates E—E shown in Figs. 1 and 3. Each of these plates E has a dimension parallel to the axis of the gear which equals or may slightly exceed the distance between the front and rear edges of the transversely extending loops 18. One plate E is disposed at the bottom of the assembled loops 18 and the other at the top, as shown in Fig. 1, so that longitudinal pressure from one block B to the other is transmitted through said plates E without compressing the loops 18. In this connection it will, of course, be understood that the combined vertical height 110

of the assembled loops 18 is less than the vertical height of the blocks B—B by an amount equal to substantially twice the thickness of each plate E.

- 5 In operation, upon inward movement of the draw bar, it is evident that the front pair of wedge blocks A—A will be forced rearwardly. As this rearward movement takes place the friction elements C—C will 10 be laterally separated or in a line perpendicular to the center line of draft. As the elements C—C are thus laterally separated, it is evident that the loops 18 of one will slide with respect to the loops 18 of the other, so that the cross portions 118—118 of the loops will compress the spring D simultaneously from both ends of the latter. In other words, the spring D will be compressed twice as fast as each friction element C is moved outwardly, thus obtaining a 15 rapid spring resistance to check the movement of the friction elements. While the front set of wedges A are moved rearwardly as heretofore described, it is also evident that the same will be moved laterally due 20 to their sliding movement on the corresponding block B. As will be understood by those skilled in the art, the action which takes place at the front or outer end of the mechanism will be duplicated at the rear end, all the elements B, C and D and the two front wedges A—A moving rearwardly bodily. In this connection, as heretofore explained, pressure from the front friction 25 element B will be transmitted to the rear friction elements B through the plates E—E.

With the arrangement shown, I am enabled to place all of the parts between the 30 sills and in a relatively short space parallel to the line of draft. At the same time, I obtain large frictional areas; it is unnecessary to extend the springs to the outsides of the sills or below the latter, and all parts 35 are such that they may be readily manufactured as ordinary castings.

Although I have herein shown and described what I now consider the preferred manner of carrying out the invention, the 40 same is merely illustrative and I contemplate all changes and modifications that come within the scope of the claims appended hereto.

I claim:

- 55 1. In a friction shock absorbing mechanism, the combination with end wedges relatively movable toward and from each other; of two like side friction elements extending between said wedges and adapted

to be separated upon relative approach of 60 said wedges, each of said side elements having integrally formed spring-receiving pockets, the spring-receiving pockets of one element being adapted to be interfitting with the spring-receiving pockets of the other 65 elements and all spring-receiving pockets, when assembled, arranged to completely encircle a spring; and a spring disposed within 70 said assembled spring-receiving pockets.

2. In a friction shock absorbing mechanism, the combination with a pair of friction elements, each element having laterally extended integral spring pockets, the spring pockets of one of said elements fitting between those of the other of said elements, 75 spring means disposed within said spring pockets when the elements are assembled, and means for separating said elements to thereby compress the spring means within 80 said pockets.

3. In a friction draft rigging, the combination with draft sills having stop-acting means, of follower-acting means, a pair of wedges associated with each of said follower-acting means, outer friction elements 85 coöperable with said wedges and adapted to be separated upon relative approach of said wedges, intermediate friction elements coöperable with said wedges at each end, means for transferring pressure from one 90 to the other of said intermediate friction elements, and spring means for resisting separation of said outer friction elements, said spring means being confined between the sills and between said wedges. 95

4. In a friction shock absorbing mechanism, the combination with end wedges; of longitudinally extending friction elements disposed between said end wedges, said longitudinally extending friction elements having integrally formed slidable interfitting spring pockets opened in a direction transverse to the planes of the spring pockets; spring means disposed within said spring pockets and adapted to be inserted transversely thereof after the spring pockets are assembled, said end wedges being relatively movable toward and from each other and said friction elements moving perpendicular to the line of relative movement between the 100 end wedges. 105

In witness that I claim the foregoing I have hereunto subscribed my name this 14 day of Feb., 1919.

JOHN F. O'CONNOR.

Witness:

CARRIE GAILING.
